Robert L. Sly, 2855 Evergreen Ave., Salt Lake City, Utah

Filed July 25, 1960, Ser. No. 61,513

Term of patent 14 years

(Cl. D54—13)

FIG. 1 is a front perspective view of a driver for a universal-joint removing tool embodying my new design;

FIG. 2 is a side elevational view thereof taken from the right of FIG. 1;

FIG. 3 is a side elevational view thereof taken from the left of FIG. 1;

FIG. 4 is a front elevational view of the driver;

FIG. 5 is a bottom plan view thereof;

FIG. 6 is a rear elevational view thereof rotated 180° from that shown in FIG. 4; and

FIG. 7 is a top plan view.

I claim:

The ornamental design for a driver for a universal-joint removing tool, substantially as shown.
